SCINTILLATING SIGN

Wallace G. McIlvanie, Yakima, Wash.

Application March 17, 1939, Serial No. 262,513

7 Claims. (Cl. 40—139)

This invention relates to scintillating signs.

An object of the invention is the provision of a sign containing indicia in which the words or other matter are included upon a surface formed by a plurality of rockable sections with means for rocking the sections alternately in opposite directions so that when the sign is illuminated it will appear in perfect form in alternation with a distorted form.

10 Another object of the invention is the provision of a sign having indicia thereon and decorations, if desired, in which the letters forming the indicia cover the flat surface of a reflecting sign which is illuminated by a lamp, the sign being formed of elongated sections superimposed upon each other in a vertical plane but rockably mounted upon horizontal axes, means being employed for rocking the sections alternately for alternately disclosing the sign and disfiguring the sign for attracting attention thereto, all of the elements of the sign and the operating means being formed as a unit.

15 A further object of the invention is the provision of a sign having a surface disposed normally in a vertical plane with the sign being formed of superimposed sections in the same vertical plane and rockably mounted on a horizontal axis, the sections being removable so that signs of various types may be applied to a rockable means, the sections being formed of transparent material having a reflecting surface at the rear thereof with the letters or other ornamentation being painted upon the surface of the sections so that when light rays are projected upon the sections the indicia on said sections will stand out, the sections being adapted to be alternately rocked for displaying the sign or for causing disfiguration of the same.

20 This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

25 Figure 1 is a front view in elevation of a sign constructed in accordance with the principles of my invention.

Figure 2 is a transverse vertical section taken along the line 2—2 of Fig. 1.

30 Figure 3 is a fragmentary end view in eleva-

tion of the operating means for the sections of the sign, and

Figure 4 is an enlarged vertical section taken along the line 4—4 of Fig. 1.

Referring more particularly to the drawing, 5 10 designates a housing which may be formed of metal or any other suitable material. This housing is vertically disposed and elongated. The upper portion of the section, as shown at 11, is curved outwardly from the back portion 10 12 and then downwardly, as shown at 13, where it terminates in a horizontal edge 14 below an elongated lamp of any suitable type.

The lower end of the housing, as shown at 16, is formed in a similar manner to that of the 15 portion 11. The front of the housing, as shown at 17, is open.

20 A bracket 20 is secured at 21 to the rear face of the housing 10 and has a flange 22 at its outer end to which is bolted the base member 23 of a motor 24. A pulley 25 is secured to the motor shaft 26.

25 A bracket 30 has a curved portion 31 neatly receiving the curved lower end 16 of the housing 10. This bracket is secured at 32 to the lower 25 end of the housing and extends rearwardly from the back 12, as shown more particularly in Fig. 2. This bracket supports a shaft 33 and a large pulley 34 is rigidly connected to the shaft.

30 To one end of the shaft 33 is secured a crank 35 while a crank 36 is secured to the other end.

35 A belt 37 is trained on the pulleys 25 and 34 so that when the motor 24 is operated the pulley 35, shaft 33 and likewise the cranks 35 and 36 are operated.

40 Elongated bars 40, 41, 42, 43 are rigidly mounted upon horizontal shafts 44 and 45. It will be seen that the bars 40 and 42 are carried by the shafts 44 while the bars 41 and 43 are carried by the shafts 45. These shafts are mounted in 40 bearings formed in the end walls 46 and 47 of the housing 10.

45 A plurality of elongated plates 50, 51, 52 and 53 are respectively connected to the outer faces of the bars 40 to 43, inclusive, by means of screws 45 54 although any other suitable fastening means may be employed for the purpose.

50 The plates 50 to 53, inclusive, have reflecting surfaces at their rear faces and these faces may be corrugated as shown at 55 in Figs. 2, 3 and 4 50 although any other suitable form of deformation of the rear faces of said plates may be had in order to give different effects when the rays of the lamp 15 are projected upon the outer faces of said plates.

A curved link 60 has one end pivotally connected at 61 to the outer rear end of a projection 58 on the bar 40 while the other end, as shown at 62, is connected to a similar projection 58 extending from the rear face of the bar 42. A rod 63 has pivotal connection with the crank 36 at one end and the other end is pivotally connected at 62 where the link 60 is connected to the projection at the rear of the bar 42.

10 A link 64 has pivotal connections at 65 and 66 with projections 59 at the rear faces of the bars 41 and 43. A rod 67 has pivotal connections with the crank 35 and also with the pin 65 so that when the shaft 33 is revolved the link 60 will rock the plates 50 and 52 in an opposite direction to that of the rocking of the plates 51 and 53 by the link 64.

From an inspection of Fig. 1 it will be seen that the letters of the words on the sign and also 20 decorations, if any, are placed upon the outer faces of the elongated plates 50 to 53, inclusive, while these plates are located in a vertical plane and some of the letters of the words may extend across the entire faces of the plates while certain 25 of the letters will extend only over a certain number of said plates. In any event the rocking of the plates and the respective bars 40 to 43, inclusive, will cause a distortion of the sign as shown in Fig. 3 when the cranks 35 and 36 are 30 disposed in a vertical plane. When the cranks, however, move to their horizontal plane, as shown in Fig. 2, the plates or sections of the sign will be in vertical alignment and the sign will appear in proper form.

35 The rotation of the shaft 33 by the pulley 34 will cause reciprocation of the rods 63 and 67 in opposite directions and therefore the links 60 and 64 will be shifted in opposite directions so that the sections of the sign will be rocked from 40 the vertical position to angular positions with respect to each other and these sections 50 to 53, inclusive, will be moved from the vertical so that the lower edges of the sections 51 and 53 will be moved inwardly while the lower portions of the 45 sections 50 and 51 will be moved outwardly with the crank 36 in the lowermost position and the crank 35 in the uppermost position. When the positions of the cranks are reversed in vertical alignment the lower edges of the sections 50 and 50 52 will be moved inwardly from the vertical while the lower edges of the sections 51 and 53 will be moved outwardly. However, as the sections reach the vertical position between these two movements of the sections the sign will appear 55 in proper form while in the other positions of the section the sign will be distorted.

Due to the fact that the sign is made up of sections as shown by plates 50 to 53, inclusive, and these plates are readily removable, other 60 sections may be substituted for the sections which are in place very readily to give an entirely different picture to the public.

The letters 70 are formed of sections and these sections are included in a number of the 65 plates 50 to 53, inclusive. Said plates are reflectors and the sections of the letters are formed on the plates with opaque paint so that the plates on opposite sides of the sections of the letters will reflect the light with the letters appearing 70 through the reflected rays.

Since the light rays from the lamp 15 are projected upon the surface of the sign at an acute angle to the surface, the light rays are then reflected downwardly at the same angle when all 75 of the sections are in a vertical plane. How-

ever, when the sections are rocked from the vertical position, the light rays will be projected in different directions so that the constant rocking of the sections will give a scintillating effect to the sign. It will be appreciated that instead 5 of the plates 50 to 53, inclusive, being the reflectors the letters 70 themselves may be the reflectors in order to give a slightly different effect from that previously explained. In other words, the plates in this case would be formed of 10 transparent material with a reflecting surface at the rear but the background may be painted out so that the letters only will reflect light rays.

The bars 40 to 43, inclusive, may be formed 15 of glass and they may be cylindrical in shape. The distance between the cranks 35 and 36 should be as short as possible so that the rocking of the plates 50 to 53, inclusive, will give a scintillating effect instead of a complete distortion 20 of the sign.

I claim:

1. A scintillating sign comprising a vertically disposed housing having a front window, a plurality of spaced horizontally disposed shafts mounted in the housing and located approximately in a vertical plane, an elongated reflecting plate secured to each shaft, said plates disposed normally in vertical alignment, indicia being applied to the plates so that the letters forming said indicia will extend over more than 30 one plate, and means for rocking alternate plates in opposite directions for alternately deflecting and aligning the plates.

2. A scintillating sign comprising a vertically disposed housing having a front window, a plurality of spaced horizontally disposed shafts mounted in the housing and located approximately in a vertical plane, an elongated reflecting plate secured to each shaft, said plates disposed normally in vertical alignment, indicia 40 being applied to the plates so that the letters forming said indicia will extend over more than one plate, means for rocking alternate plates in opposite directions for alternately deflecting and aligning the plates, and means projecting light 45 rays on to the plates.

3. A scintillating sign comprising a vertically disposed housing having a front window, a plurality of spaced horizontally disposed shafts mounted in the housing and located approximately in a vertical plane, an elongated reflecting plate secured to each shaft, said plates disposed normally in vertical alignment, indicia being applied to the plates so that the letters forming said indicia will extend over more than one 55 plate, means for rocking alternate plates in opposite directions for alternately deflecting and aligning the plates, and means for removably connecting the plates to the shafts.

4. A scintillating sign comprising a housing 60 having a front window substantially vertically disposed, a plurality of elongated rockably mounted reflecting plates disposed in vertical alignment at the window and having indicia applied thereto with the letters of the indicia extending over more than one plate, a lamp confined in a post of the housing and projecting light rays on to the plates, and means for rocking alternate plates in opposite directions for 70 alternately deflecting and aligning the plates.

5. A scintillating sign comprising a housing having a front window substantially vertically disposed, a plurality of elongated rockably mounted reflecting plates disposed in vertical 75

alignment at the window and having indicia applied thereto with the letters of the indicia extending over more than one plate, a lamp confined in a post of the housing and projecting light rays on to the plates, and means mounted on the back of the housing for rocking alternate plates in opposite directions and forming a unit with the housing.

5 6. A scintillating sign comprising a housing having a front window substantially vertically disposed, a plurality of elongated rockably mounted reflecting plates disposed in vertical alignment at the window and having indicia applied thereto with the letters of the indicia extending over more than one plate, a lamp confined in the post of the housing and projecting light rays on to the plates, means mounting the individual plates for rocking movement, means connecting alternate plates for simultaneous

rocking movement, and means causing rocking of alternate plates in opposite directions.

7. A scintillating sign comprising a housing having a front window substantially vertically disposed, a plurality of elongated rockably mounted reflecting plates disposed in vertical alignment at the windows and having indicia applied thereto with the letters of the indicia extending over more than one plate, a lamp confined in a post of the housing and projecting light rays on to the plates, a shaft for each plate having bearings at the ends of the housing, a bar secured to each shaft, means removably securing the plates to the bars, means connecting alternate bars for simultaneous rocking movement, and means attached to the connecting means for causing rocking of alternate bars and the associated plates in opposite directions.
